CONTROL SYSTEM

Walter Schaelchlin, Pittsburgh, and Earl H. Hornbarger, Edgewood, Pa., assignors to Westinghouse Electric Corporation, East Pittsburgh, Pa., a corporation of Pennsylvania

Application September 28, 1944, Serial No. 556,160

6 Claims. (Cl. 172—179)

This invention relates, generally, to an electric drive and, more particularly, to an electric drive embodying an electric motor and which includes means for reversing the direction of rotation of the motor.

In certain applications of reversible electric drives space limitations are such that standard reversing equipment will not fit into the allowed space. It is also frequently required that the motor be entirely disconnected from the line when the system is stopped. Ordinarily in a reversible electric drive in which the motor is to be disconnected from the line at a minimum there is required one main line contactor and a pair of two-pole mechanically interlocked contactors for reversing the connections to the motor armature.

A compact design is obtainable by utilizing, in place of the reversing contactors, an electromagnetically operated switch which is maintained in either of its two operative positions with the actuating coils thereof deenergized. Such a reversing controller differs from conventional arrangements in that the reversing elements are always in one or the other of the two operating positions. In other words, the controller is always positioned for either forward or reverse operation of the motor and the motor will start as soon as the line contactor closes. Thus suitable provision should be made to prevent closing of the main line contactor until the reversing switch or controller is in the desired position.

A principal object of this invention is to provide a reversible electric drive which is inherently compact in design and simple in operation.

Another object of this invention is to provide a reversible electric drive which utilizes a simple reversing switch operable to either of its two positions, in which the reversing switch automatically assumes its correct forward or reverse position before the motor is connected to the line.

Another object of this invention is to provide a reversible electric drive in which low voltage protection is provided.

Another object of this invention is to provide a reversible electric drive in which the reversing switch or controller is operated only to effect reversing of the direction of rotation of the motor and is not energized and therefore does not function during starting of the motor in the same direction as last operated.

Another object of this invention is to provide an electric drive of the character mentioned in which the motor must be deenergized before a reversing cycle can be initiated.

Other objects and advantages will become ap-

parent from a study of the following disclosure when considered in conjunction with the accompanying drawing, in which the single figure thereof illustrates a reversible electric drive embodying the principles of this invention.

5 Referring now to the drawing, the reversible electric drive therein illustrated comprises generally a direct-current motor M which is reversely operable, a reversing switch generally designated RS for establishing reversing connections for the motor armature, forward and reversing push buttons respectively designated FWD and REV which selectively energize the forward and reversing solenoids F and R of the reversing switch, an accelerating relay designated A which controls the starting cycle of the motor M and in addition initiates an energizing circuit for the coil of the main line contactor, which contactor is designated MC, and as the final general control element the main line contactor MC which establishes energizing circuits for the motor.

The motor M, as illustrated, comprises a pair of field windings, one a shunt field winding designated SHF and the other a series field winding designated SRF. While two field windings have been shown for this motor it will, of course, be understood that any suitable field winding arrangement may be utilized. For example, the motor may be a series motor or a shunt motor depending upon the operating characteristics which are desired. The armature winding of the motor M is connected through either the forward or reversing elements of the reversing switch and the contacts MC1 and MC3, across the energizing buses B1 and B2. When the reversing switch is in the position indicated in the drawing, that is the forward position, the contact members F3 and F4 thereof establish connections to energize the motor armature in a direction with respect to the motor field system such that the motor will operate in a forward direction. The contact members F2 operate in conjunction with the front contacts of the forward push button and the back contacts MC4 to connect the coil of the accelerating relay A across the main line buses. The contact members F1, when closed, provide an energizing circuit for the coil of the forward solenoid, in conjunction with the contacts AP1 of the anti-plugging relay AP and the contacts 10 MC2 when the forward push button is depressed, to effect operation of the reversing switch to its forward position. This circuit may not be completed if a voltage appears across the motor armature terminals of sufficient magnitude to operating the anti-plugging relay. The contacts MC2.

when the main line contactor is operated, also open this energizing circuit. For reverse operation of the motor the contact members R3 and R4 reversely energize the motor armature and thus cause the motor to operate in the reverse direction. The contact members R2, when closed, like the contact members F2, form part of an energizing circuit for the coil of the accelerating relay A. The contact members R1 form part of an energizing circuit for the coil of the reversing solenoid R.

The accelerating relay A controls the starting cycle of the motor at its contact members A1 which shunt the starting resistor SR. This relay picks up once the reversing switch is in its correct position and opens the shunt circuit around the starting resistor at its contacts A1. Thus when the motor accelerates from zero speed, the starting resistor is connected in series with the armature winding and the series field circuit to thus limit the armature currents within permissible values. This is desirable in the case of a motor which is permanently connected to the load which it drives since under this condition the motor armature currents at very low speeds and high torque may be excessively high. The accelerating relay at its contact members A2 also forms part of an energizing circuit for the coil of the main line contactor. Thus this contactor may not be closed to energize the motor until the accelerating relay has operated. Likewise, the accelerating relay may not be operated, as hereinbefore noted, until the reversing switch is in its correct position depending upon which of the forward and reverse push buttons is depressed.

The main line contactor at its contacts MC1 and MC3 energizes the motor circuits. Its contact members MC2 open the energizing circuit for the coils of the forward and reverse solenoids which comprise part of the reversing switch. The contact members MC4 open the energizing circuit for the accelerating relay thus causing it to drop out shortly after the main line contactor operates. Thus the resistor SR is inserted in the motor circuit for a short interval just sufficient to bring the motor from zero speed up to some higher speed, and then is shunted to permit the motor to accelerate over the rest of its speed range. The contact members MC5 in conjunction with the stop push button, so designated in the drawing, form an energizing circuit for the coil of the main line contactor to keep this coil energized when the contact members A2 open.

The operation of the system is as follows. If it is desired to operate the motor in a forward direction, the forward push button is depressed. This establishes an energizing circuit for the coil of the accelerating relay since the reversing switch is in its forward position, which begins at the bus B1 and includes the stop push button, the back contacts of the reversing push button, the front contacts of the forward push button, the contact members F2 now closed, the coil of the accelerating relay and the contact members MC4 to the bus B2. This accelerating relay thus picks up and opens its contact members A1 to insert the starting resistor in the motor circuit and closes its contact members A2 to complete an energizing circuit for the coil of the main line contactor which includes the stop push button, the back contacts of the reversing push button, the front contacts of the forward push button, the contacts F2, the contacts A2 and the coil of the main line contactor to the bus B2.

The main line contactor immediately picks up, closing its contact members MC1 and MC3 and immediately starts the motor in the forward direction. At this time the contacts MC4 open and deenergize the coil of the relay A. This relay now drops out and shunts the starting resistor from the motor circuit. The contact members MC5 close before the relay A drops out and maintain the coil of the main line contactor energized. Since the contact members MC2 have opened, the energizing circuit for the coil of the reverse solenoid is opened at this point. This actuation of the reversing push button may not complete an energizing circuit for the reverse coil. After the motor armature voltage builds up the anti-plugging relay AP is operated, thus opening its contact members AP1 also in the energizing circuit for the forward and reverse solenoids. By reason of these expedients the motor may not be suddenly reversed in its direction of operation by operation of either the forward or reverse push button. To accomplish reversing of the motor it is necessary to press the stop button and deenergize the main line contactor. When the main line contactor is deenergized its contact members MC2 close. If these contacts alone maintained the energizing circuit for the forward and reversing solenoids open, it would be possible immediately upon deenergization of the main line contactor to initiate a reversing cycle of the motor. This is prevented, however, by the anti-plugging relay which will not drop out until the motor armature terminal voltage has decreased to a fairly low level, at which level a reversing cycle may be initiated without damage to the motor.

If it had been desired to start the motor in the reverse direction with the reversing switch in the forward position, the reversing push button would have been depressed, immediately energizing the coil of the reversing solenoid in a circuit through the stop push button and the forward and reverse push buttons which includes, the contacts R1, AP1 and MC2. The magnetic forces acting on the core of the reversing solenoid accelerate the reversing switch to the right. This immediately opens the contacts R1 to deenergize the coil R. The assembly, however, by reason of its inertia, moves to its extreme reverse position and closes the contacts R2, R3 and R4. The contacts R2 energize the coil of the accelerating relay A and the contacts R3 and R4 establish reversed armature connections for the motor to operate the motor in its reverse direction. The main line contactor now closes to start the motor and deenergize the accelerating relay.

Since the reversing switch operates only during periods when the motor circuits are deenergized its contacts do not interrupt energized circuits. This relay may therefore be of fairly small capacity, thus lending itself to small physical design. Further, the coils of the reversing solenoids are only intermittently energized and are deenergized by contacts within the reversing switch itself. The coils may thus be intermittently rated. In controllers which would be reversed very infrequently the reversing switch illustrated in the drawing would receive correspondingly infrequent operation. In the case of contactor-type reversing controllers the reversing devices would open and close every time the motor was started.

The reversing switch, as illustrated in the drawing, is schematically shown for the sake of simplicity and it should be understood that any

physical arrangement of parts for this switch which embody the principles illustrated may be utilized. One form of such switch which has been found satisfactory and which is not affected by shock involves a cam shaft and a pair of separate switch units operated in the alternate positions of the cam shaft. The cam shaft is operated to its two positions by means of two small electromagnetic elements which are mechanically linked thereto.

The foregoing disclosure and the showing made in the drawing are merely illustrative of the principles of this invention and are not to be interpreted in a limiting sense. The only limitations are to be determined from the scope of the appended claims.

We claim as our invention:

1. In an electric drive, the combination of, a motor, a contactor for energizing the motor, a relay having a pair of coils for actuating said relay to either of two positions depending upon which coil is energized, means for selectively energizing said pair of coils, said relay being effective in each of its two positions to effect reversing of said motor, and means for deenergizing the energized coil of said relay upon movement thereof under influence of said energized coil.

2. In an electric drive, the combination of, a motor, means for energizing the motor, reversing means for reversing the energization of the motor, first control means for controlling said reversing means, second control means operated by and operable in conjunction with said reversing means for effecting operation of said means for energizing the motor, and means for deenergizing said second control means upon operation of said means for energizing said motor.

3. In an electric drive, the combination of, a motor, a contactor for energizing the motor, a switch having a pair of coils for effecting operation thereof to either of two positions upon separate energization thereof, means for selectively energizing said pair of coils, a relay for energizing the contactor, means forming a part of said switch for energizing said relay when said switch is in the position selected by said means for selectively energizing said coils; and means forming a part of said contactor, for deenergizing said relay when said contactor is energized and operated.

4. In an electric drive, the combination of, a motor, a contactor for energizing the motor, a switch having a pair of coils for effecting opera-

tion thereof to either of two positions upon separate energization thereof, means for selectively energizing said pair of coils, a relay for energizing the contactor, means forming a part of said switch for energizing said relay when said switch is in the position selected by said means for selectively energizing said coils; means forming a part of said contactor for deenergizing said relay when said contactor is energized and operated, a resistor connected in series with said motor, and means forming a part of said relay normally shunting said resistor when said relay is deenergized.

5. In an electric drive, the combination of, a motor, a contactor for energizing the motor, a switch having a pair of coils for effecting operation thereof to either of two positions upon separate energization thereof, means for selectively energizing said pair of coils, a relay for energizing the contactor, means forming a part of said switch for energizing said relay when said switch is in the position selected by said means for selectively energizing said coils, means forming a part of said contactor for deenergizing said relay when said contactor is energized and operated, a resistor connected in series with said motor, means forming a part of said relay normally shunting said resistor when said relay is deenergized, and means for preventing energization of either of said pair of coils as long as said motor is energized.

6. In an electric drive, the combination of, a motor, a contactor for energizing the motor, a switch having a pair of coils for effecting operation thereof to either of two positions upon separate energization thereof, means for selectively energizing said pair of coils, a relay for energizing the contactor, means forming a part of said switch for energizing said relay when said switch is in the position selected by said means for selectively energizing said coils, means forming a part of said contactor for deenergizing said relay when said contactor is energized and operated, a resistor connected in series with said motor, means forming a part of said relay normally shunting said resistor when said relay is deenergized, and a relay energized according to the motor voltage and having contacts which maintain the energizing circuits for said pair of coils open as long as the motor voltage is above a predetermined value.
